UNITED STATES PATENT OFFICE

SERAPHINE F. BAUWENS, OF CHICAGO, ILLINOIS

DECORATIVE BOW FOR HAT BANDS OR THE LIKE

Application filed November 20, 1929. Serial No. 408,438.

Bands formed from ribbon for use as hat bands, arm bands or the like are usually ornamented by forming decorative bows thereon, the bows usually being made to simulate a bow-knot with one or more loops extending in each direction from the center of the bow longitudinally along the ribbon and having a transversely extending central section between the loops arranged to contrast with the rest of the bow. In a true bow-knot formed from ribbon this contrast between the central section and the rest of the bow results from the fact that the central section of the bow is formed by a part of the ribbon extending transversely across the front of the bow and constituting the knot which holds the bow in proper shape.

To obtain this same contrasting effect in ornamental bows which are not true bow-knots, it has been customary to use a separate piece of ribbon extending transversely across the forward side of the principal ribbon between the loops and sewed in proper position thereon. Such bows, however are not entirely satisfactory since they are not adapted for rapid production, either manually or by the use of machines and do not retain their shape when used.

The primary object of the present invention is to provide a new and improved decorative bow which is particularly adapted for rapid production either manually or by machine and which is neat in appearance, retains its shape, and effectively simulates a bow-knot.

Another object is to provide such a bow into which means may easily be incorporated to stiffen the bow transversely.

Another object is to provide such stiffened bow in which the stiffening means cooperates with the ribbon to form one of the loops of the bow.

Other objects and advantages will become apparent from the following description taken in connection with the accompanying drawing, in which:

Figure 1 is a front view of a double loop bow embodying the invention in its preferred form.

Fig. 2 is an enlarged longitudinal sec-

tional view of the bow shown in Fig. 1, taken along the line 2—2 of Fig. 1.

Fig. 3 is a rear view of the bow shown in Figs. 1 and 2.

Fig. 4 is a front view of a single loop bow formed similarly to the bow shown in Figs. 1 to 3.

Fig. 5 is an enlarged longitudinal sectional view of the bow shown in Fig. 4, along the line 5—5 thereof.

Fig. 6 is a front elevational view of an alternative form of bow of the single loop type.

Fig. 7 is an enlarged longitudinal sectional view of the bow shown in Fig. 6, along the line 7—7 thereof.

While I have shown in the accompanying drawing and will herein describe in detail the preferred embodiment of the invention together with two alternative forms thereof, it is to be understood that this disclosure is given for the purpose of illustrating the invention and is not intended as a limitation of the invention to the constructions disclosed. In the appended claims, I aim to cover all modifications and alternative constructions falling within the spirit and scope of the invention.

In Figs. 1 to 3 of the drawing the invention is illustrated as embodied in a bow 10 formed on a ribbon 11 adapted for use as a hat band. When such ribbons are secured in position about the crown of a hat (not shown) the two ends thereof are concealed beneath the bow, and the bow 10 is, therefore, formed near one end of the ribbon 11 as shown in Fig. 3.

To provide for economical production, bows made in accordance with the present invention are composed of a plurality of flutes or transverse folds of various sizes formed from the ribbon and held in place by means which may be placed in position as an incident to the fluting operation, the different sizes of flutes being arranged in various ways to give the bow the appearance of a bow-knot.

In the form shown in Figs. 1 to 3, the bow 10 has a flat central section 12 at both ends of which a plurality of comparatively small flutes or folds 13 are formed to provide a definite contrasting border 14 for the central

section. At the outer side of each border 14, a comparatively large fold 15 is formed, extending from the forward side of the ribbon so as to constitute two of the end loops of 5 the bow.

To hold the folds 13 and 15 in proper form and to assist in keeping the central section 12 stretched tightly, suitable fastening means preferably in the form of a plurality of wires 10 or tie pins 16 (Figs. 2 and 3) extend through the folds in such a manner as to be invisible from the forward side of the bow. At their ends the wires 16 are reversely bent as shown at 17 against the rear edges of the folds so 15 that the folds cannot be displaced longitudinally off the ends of the wires.

The folds 13 and 15 are held against displacement toward the center of the wires by means which also acts to stretch the central 20 section 12, this means preferably being positioned between the wires 16 and the ribbon which forms the central section 12. In the form shown, this means comprises a substantially rigid flat member 18 formed from cardboard, the member being of slightly less width than the ribbon (as shown in Fig. 3) so as to be effectively concealed behind the ribbon. The member 18 is positioned between the central section 12 and the wires 16 so that 25 the edges of the member engage the ribbon to hold the folds 13 and 15 tightly compressed against the bent ends 17 of the wires 16. Although the member 18 will normally be held in proper transverse position by the pressure 30 of the folds 13 on the ends thereof, it may be fixed positively against displacement by running one wire 16 (the upper one) through the member 18 as shown in dotted outline in Fig. 3.

40 While the transverse folds 13 and 15 and the member 18 impart considerable transverse rigidity to the bow 10, it may be further stiffened through the use of a suitable lining in the form of a strip 19 (Figs. 2 and 3) of hair cloth or the like of less width than the ribbon. The strip 19 is positioned along the back side of the ribbon 11 so as to be concealed thereby and is interfolded with the ribbon 11 in the formation of the folds 45 13 and 15. In order that the strip 19 may be easily formed into folds, the hair (not shown) runs transversely thereof so that the strip is flexible longitudinally and stiffened transversely.

50 55 In case it is desired to make the bow 10 simulate a double bow-knot, one end of the lining strip 19 may be sewed to the ribbon 11 along a transverse line indicated at 20 in Fig. 2, spaced from the ends of the wires 16, 60 the length of the ribbon between the line 20 and the wires 16 being greater than the length of the lining strip so that the ribbon will form a loop 21 (Figs. 1 and 3) extending away from the center of the bow beyond the 65 adjacent loop 15. By this construction the

loop 21 may be formed by the use of a comparatively small additional amount of ribbon.

A corresponding loop 22 may be provided 70 at the other end of the bow by reversely folding the short end of the ribbon and securing the same over the ends 17 of the wires 16. To facilitate this operation, the ends 17 of some wires 16, preferably the top and bottom wires, 75 may be sharpened as shown in Figs. 2 and 3 so as to constitute hooks. These hooks may be utilized in fastening the band on the crown of a hat since in this operation the right or long end of the ribbon (Figs. 1 and 3) may be suitably secured to the hat as by stitching, and after the ribbon has been 80 stretched about the hat, the end having the bow 10 thereon may be fixed in place by engaging the hooks with the fixed end of the ribbon 11.

In the form shown in Figs. 4 and 5 a bow 10^a of the single loop type, is formed on a ribbon 11^a in the same general manner as the bow 10 shown in Figs. 1 to 3, with a flat central section 12^a, borders 14^a at the ends of the central section formed by small folds 13^a, and end loops formed by large folds 15^a. Similar wires 16^a projecting through the folds 13^a and 15^a and reversely bent over the back edges of the folds at 17^a cooperate with a cardboard member 18^a to maintain the folds in proper form. A hair cloth liner 19^a may also be inter-folded with the ribbon 11^a to 95 stiffen the bow against transverse bending 100 and to round out the folds.

Another alternative embodiment of the invention is shown in Figs. 6 and 7 wherein a bow 10^b is formed on a ribbon 11^b, the construction of this bow also being such that it lends itself to rapid production. In this form the entire central section 12^b is formed by a series of transverse folds or flutes 13^b which produce a ribbed effect which contrasts with the remainder of the ribbon. At each end of the central section 12^b, a larger fold 15^b is formed, projecting from the forward side of the ribbon 11^b to provide the end loops of the bow.

105 The means for securing the folds 13^b and 15^b in the desired form preferably comprises one or more wires 16^b extending through the folds and reversely bent along the rear edges of the folds as indicated at 17^b. Transverse stiffening may be provided where desired by the use of a hair cloth liner 19^b extending along the back side of the ribbon 11^b and inter-folded therewith.

110 From the foregoing description it will be apparent that the invention provides a neat appearing bow for hat bands or the like which will retain its form when used and which may be manufactured economically since it is adapted to be made by machinery. It will also be seen that a double bow has 115 been provided which may be made without 120 125 130

materially increasing the amount of material required.

While the invention has herein been described with particular reference to ribbons 5 adapted for use as hat bands, it is to be understood that this is not to be taken as a limitation of the invention to such a use, since the bows are equally as well adapted for other uses, such as on arm bands or as ornaments not used in connection with bands of any kind.

I claim as my invention:

1. In a ribbon adapted for use as a hat band or the like, a bow formed from said ribbon and having a strip of hair cloth positioned along the back thereof, said strip being narrower than said ribbon and having the hair extending transversely thereof, said ribbon and said strip having a flat section extending longitudinally thereof and forming the central section of the bow, and a plurality of small transverse folds in said ribbon and said strip at each end of said section to provide a contrasting border for said section, a 25 larger transverse fold formed in the ribbon and the strip at the outer side of each of said borders, a plurality of wires extending behind said section and through said folds, the ends of said wires being reversely bent along the back of the folds to prevent displacement of the folds toward the ends of the wires, means between said wires and said ribbon to prevent displacement of said folds toward the center of said wires, said strip extending beyond one end of said wires and being attached to said ribbon to form another outwardly extending fold, the reversely bent portions of one of the wires at the other end of the bow being in the form of a hook for 40 engaging the ribbon to form a circular band.

2. A decorative bow comprising a ribbon, a strip of hair cloth positioned behind the ribbon for transversely stiffening the same, said ribbon and said strip having a flat portion and a plurality of small transverse folds at the end thereof forming a contrasting central section for the bow, a larger transverse fold formed in said ribbon at each end of said section, a plurality of wires extending through said folds and having their ends reversely bent along the rear sides of said folds, and means intermediate said wires and said flat portion to prevent displacement of said folds toward the center of said section and maintain a smooth surface on said portion.

3. A decorative bow comprising a ribbon, a strip of hair cloth positioned behind the ribbon for transversely stiffening the same, said ribbon and said strip having a flat portion and a plurality of small transverse folds at the end thereof forming a contrasting central section for the bow, a larger transverse fold formed in said ribbon at each end of said section, a plurality of wires extending through said folds and having their ends

reversely bent along the rear sides of said folds, and means intermediate said wires and said flat portion to prevent displacement of said folds toward the center of said section and maintain a smooth surface on said portion, one of said wires having a hook formed thereon for use in securing said bow in position on a hat or the like.

4. A bow for hat bands or the like formed from ribbon and comprising a flat section of said ribbon forming the central section of the bow, a substantially rigid flat member behind said section, a plurality of small transverse folds of ribbon at each end of said flat section to form a contrasting border for said section, a larger transverse fold of said ribbon extending from the forward side of the ribbon at each end of said borders and forming the end loops of the bow, a plurality of wires extending across the rear side of said rigid member and through said folds, and means at the ends of said wires to hold said folds against movement away from said rigid member.

5. A decorative bow comprising a ribbon formed to provide a flat central section for the bow, a plurality of transverse flutes along each vertical edge of said central section forming a contrasting border for said section, a larger transverse fold at the outer edge of each border to form the end loops of the bow, and means to hold said folds and said flutes in proper position.

6. A decorative bow comprising a ribbon formed to provide a flat central section for the bow, a plurality of small transverse folds in the ribbon at each end of said flat section to form a contrasting border therefor, a larger transverse fold at the outer edge of each border to form the end loops of the bow and means operable to hold the folds in proper position including a plurality of wires extending longitudinally of the ribbon.

7. A decorative bow comprising a ribbon having a flat central section, a large transverse fold formed in the ribbon at each end of said section and projecting from the forward side of said ribbon to form the end loops of the bow, a plurality of wires extending longitudinally along the back side of said ribbon and through said folds, the ends of said wires being reversely bent to prevent displacement of said folds off of the ends of said wires, and means for preventing displacement of said folds toward the center of the bow.

8. In a bow for hat bands or the like formed from ribbon, a strip of transversely stiffened cloth positioned along the back side of the ribbon, said strip being of slightly less width than said ribbon, said ribbon and said strip being bent to form a plurality of transverse flutes, said ribbon and said strip also being bent to form folds adjacent said flutes and constituting the loops of the bow,

- said loops being positioned on the forward side of the ribbon, and a wire extending through said flutes and said folds and operable to hold the same in position.
- 5 9. In a ribbon adapted for use as a hat band or the like, a bow comprising a plurality of small transverse folds formed from the ribbon, larger folds adjacent said small folds and projecting from the forward side 10 of the ribbon, and a plurality of wires extending transversely through said folds, the ends of said wires being reversely bent along the back side of said folds.
- 15 10. An ornamental bow comprising a piece of ribbon, a strip of transversely stiffened material behind said ribbon, the ribbon and said strip having a plurality of small transverse folds formed therein so that the folds in the ribbon are visible on the forward side 20 of the ribbon, a larger transverse fold formed in the ribbon and the strip at each end of the small folds and projecting from the forward side of the ribbon so that the folds in the ribbon are visible on the forward 25 side of the ribbon and form the end loops of the bow, and means engaging said folds to hold the same in position.
- 30 11. An ornamental bow formed from a single piece of ribbon to provide a plurality 35 of small transverse folds in the ribbon along each edge of the central section of the bow, a larger transverse fold at each end of said small folds projecting from one side of the ribbon to form the end loops of the bow, and means to maintain said folds in proper position.
- 40 12. A decorative bow comprising a ribbon having a plurality of small transverse folds therein along each edge of the central section 45 of the bow and a larger transverse fold at each side of said central section projecting from the forward side of the ribbon to form the end loops of the bow, and means for securing said folds together, said means providing a hook for use in securing the bow in 50 position on a hat or the like.
- 55 13. A decorative bow comprising a ribbon, a transversely stiffened member along the back side of said ribbon, said member and said ribbon having a flat section and a plurality of small transverse folds at each end of the flat section to form a contrasting border therefor, a larger transverse fold formed in said ribbon and said member at each end 60 of said section, means to hold said folds in proper form, and means on the bow forming a hook for use in mounting said bow.
- 65 14. A decorative bow comprising a single piece of ribbon formed to provide a flat central section for the bow, a large forwardly extending transverse fold at each end of said section, and means operable to hold the inner ends of said folds together, said means including a wire concealed by the ribbon and

extending through the material of the ribbon longitudinally thereof.

15. A bow comprising a single piece of ribbon with a plurality of forwardly extending transverse folds therein to form the end loops of the bow, and means for holding the inner ends of said folds together including a wire concealed by said ribbon and extending longitudinally through the material of the ribbon and having a hook formed near 75 one end of the bow for mounting said bow.

16. A bow comprising a ribbon, a stiffening strip behind said ribbon, said strip and said ribbon having a pair of transverse folds therein to form end loops for the bow, and means for holding said folds in position including a wire extending longitudinally of said ribbon, said strip and said ribbon being attached to each other to form a second end loop on one end of the bow.

In testimony whereof, I have hereunto affixed my signature.
